UNITED STATES PATENT OFFICE

2,609,922

COSMETIC CONTAINER

Frederick R. Book, Jr., Waterville, Conn., assignor
to The Eyelet Specialty Company, Waterbury,
Conn.

Application August 15, 1950, Serial No. 179,420

2 Claims. (Cl. 206—56)

1

This invention relates to holders or containers for cosmetics and particularly those which are provided in stick form, such as lipsticks and the like.

One of the objects of the invention is to provide a holder or container of this character of simple form, which may be inexpensively made and economically sold and which will be provided with a minimum of parts yet shall be positive and effective in operation and can be operated with one hand.

More particularly, the invention contemplates the provision of an outer or body shell of tubular form, closed at one end and open at its other end, and having a cosmetic cup or lipstick holder slidably mounted within the body shell and being thus capable of movement toward or away from the open end of the same. The body shell is provided in its side wall with an aperture bounded by a pair of laterally-extending lugs or ears within which is rotatively mounted a roller that projects through the aperture in the wall of the body shell and has its peripheral edge in frictional contact with the surface of the cosmetic cup, thus providing an arrangement by means of which rotative movement of the roller will cause the cosmetic cup to be advanced or retracted, such movement being limited by stop means provided on the cosmetic cup.

With these and other objects to be hereinafter set forth in view, I have devised the arrangement of parts to be set forth and more particularly pointed out in the claims appended hereto.

In the accompanying drawing, wherein an illustrative embodiment of the invention is disclosed, Fig. 1 is a side elevation of a cosmetic container constructed in accordance with the invention; Fig. 2 is a view taken at right angles to Fig. 1 of the container, with its closure cap removed and the cosmetic carrier or cup advanced to expose the cosmetic out of the open end of the body shell; Fig. 3 is a sectional view taken on the line 3—3 of Fig. 2, looking in the direction of the arrows; Fig. 4 is a side elevation of the cosmetic carrier or cup; Fig. 5 is a sectional view taken on the line 5—5 of Fig. 3, looking in the direction of the arrows, and Fig. 6 is a sectional view on a slightly enlarged scale, taken on the line 6—6 of Fig. 4, looking in the direction of the arrows.

Referring to the drawing, 1 indicates the body shell of the container, the same being of cylindrical form and preferably composed of metal, plastic or other suitable material. At one end, the body shell 1 is closed as indicated at 2, and the same is provided with an opposite open end 3 out

of which the cosmetic material, which might be lip rouge or other cosmetic, or other material in stick form and shown at 4, is projected preparatory to application to the lips.

5 The lipstick or other cosmetic material 4 is mounted in a holder consisting of a carrier or cup 5 shown most clearly in Fig. 4. It will be therein noted that this carrier is of tubular cup-shaped form and is provided with a central, reduced-diameter portion 6. At its forward end it is provided with a larger-diameter part 7 in which the cosmetic stick 4 is fitted and from which it protrudes. At the opposite end of the carrier is fitted a closure plug 8 which closes said end of the carrier and forms a large diameter part 16 corresponding in diameter to that portion indicated at 7 located at the opposite end of the carrier. The large-diameter portions 7 and 8 are of a size that the same closely fit within the body shell 1 but permit easy slidable movement of said carrier within the shell and in a direction axially of the shell. Such slidable movement serves to either advance the carrier to expose its cosmetic material 4 out of the open end 3 of the shell, as indicated in Figs. 2 and 3, or else retracts the cosmetic material within the shell and permits the placement of the cover or closure cap 9 over the open end 3 of the shell.

10 The means for moving the cosmetic carrier or cup in the manner described, consists of a roller 10 preferably composed of soft rubber or other suitable resilient material. Said roller 10 is provided with an axle or pin 11 rotative in laterally-extending lugs or ears 12 formed out of material 15 of the body shell 1, such material being provided by the formation of an aperture 13 in the side wall of the shell 1. The axle 11 can be rotative in these ears or the axle can be fixed and the roller rotative on it. The aperture 13 permits the protrusion of a portion of the edge or periphery of the roller into the shell 1 and into frictional contact with the surface of the reduced-diameter portion 6 as shown at 18. This arrangement is such that when the roller is manually rotated by sliding movement of the thumb held against it, it will, through its frictional contact with the surface of the cosmetic carrier or cup 5, cause said carrier to be advanced toward the open end 2 of the shell or else retracted into the shell, according to the direction of rotation of the roller.

15 The provision of the closure plug 8 at the inner end of the carrier, results in the formation of an annular shoulder 14 near the inner end of the carrier or cup 5 and said shoulder acts as a stop or abutment that comes into contact with the roller

10 when the carrier or cup 5 is moved to its limit of advancement out of the shell 1 and prevents further advancing movement of the carrier. The portion 7 also has a shoulder 15 at its inner end which may act as a stop against the roller to limit the retracting movement of the carrier 5 within the shell 1, or this retracting movement can be halted by the inner end of the carrier coming into contact with the closed end 2 of the shell 1.

From the foregoing, the operation of the cosmetic container will be apparent. By manual rotative movement of the roller 10, produced by sliding movement of the thumb held against it, the roller will, by its frictional engagement against the surface of the cosmetic carrier, cause said carrier to be advanced or retracted as desired, the advancing movement of the carrier being limited by the shoulder 14 coming into contact with the roller. Through the arrangement described a simple and economical structure is provided which is smooth and effective in operation, requiring the use of only one hand for advancing or retracting of the lipstick.

While I have herein described the improved structure for use in connection with lipstick, it is obvious that the same may be used for other materials and purposes, such uses being intended as within the scope of the claims appended hereto.

What I claim is:

1. A cosmetic container comprising, a tubular body shell closed at one end and open at its other end, a cosmetic cup having a central cylindrical small-diameter portion and wider-diameter portions at its opposite ends, the wider-diameter portions closely fitting the inside of the body shell but permitting axial sliding movement of the cosmetic cup within the body shell, the body shell being provided with an aperture in its wall, a compressible roller rotatively mounted on the out-

5
10

side of the shell and projecting through the aperture and having its edge in frictional contact with the cylindrical surface of the small-diameter portion of the cosmetic cup to thereby frictionally engage against said cylindrical surface and cause sliding movement of the cosmetic cup when the roller is manually rotated, the sliding movement of the cup being limited at least in one direction by engagement of the roller with the end of one of the wider-diameter parts of the cosmetic cup.

2. A cosmetic container comprising, a cylindrical, tubular body shell closed at one end and open at the other end, a cosmetic cup of cylindrical form closely fitting and slidably mounted within the shell, said cup being provided with a rearwardly-extending stem of less diameter than the cup and of cylindrical form, said stem having a disk shaped head at its end remote from the cup, said disk shaped head being of a diameter substantially the same as that of the cup and of greater diameter than the stem, a soft roller rotatively mounted on the outside of the shell, the shell having an aperture through which the roller partly protrudes to enter into the shell and frictionally contact the stem of the cosmetic cup, the cup and the head on the stem acting as stops in cooperation with the roller to limit the advancing and retracting movements of the cup relatively to the shell.
